UNITED STATES PATENT OFFICE.

IRVING JACKSON, OF NEW YORK, N. Y.

RADIATOR INCLOSURE.

Application filed March 21, 1927. Serial No. 176,882.

This invention relates to a device for enclosing a radiator or similar heating device.

My invention has for an object to provide a radiator cover which will present an appearance analogizing the furnishings of a house while restricting the circulatory action of the heated air to a minimum degree.

A further object of the invention is to provide a radiator cover having a top which is protected by a baffle spaced away from the top with common vents for the space below and above the baffle.

To attain these objects and such further objects as may appear herein or be hereinafter pointed out, I make reference to the accompanying drawing forming a part hereof, in which—

Figure 1 is a perspective view of my device with parts broken away to disclose the interior construction;

Figure 2 is an enlarged, broken section of a corner in side elevation;

Figure 3 is a vertical transverse sectional view.

The device comprises a housing, indicated generally by the numeral 10, comprising end walls 11 and a front wall 12, comprising in their structure corner posts 13, 14 and 15, and horizontal members 16, 17 and 18.

The corner posts and horizontal members have their inner edge rabbeted as at 19 and within the rabbet thus formed a reticulated or foraminous sheet 20 is secured in any approved manner as by the bead 21.

As it is desirable to protect the wall adjacent the radiator from the effect of the rising current of air, a back wall 22 is also provided and all of the walls are supported upon beams 23 and 24 which in turn are preferably supported upon legs 25, such legs, however, forming no essential part of the invention.

The exterior of the housing is completed by the use of a top 26 lined upon its under sur-

face by an insulating sheet 27. The top horizontal member 17 is provided adjacent the top 45 26 with a row of openings 28 formed preferably in a straight line parallel with such top. Spaced below the top 26 is a baffle plate 29 having its front edge set in a groove 30 which transects the openings 28 defining a 50 space 31 between such baffle 29 and the insulating sheet 27. The rear edge of the baffle 29 is similarly spaced by a filler strip 32.

For the purpose of obscuring the openings 28 and also for deflecting the current of air 55 emerging therefrom downwardly, a molding strip 33 is attached to and depends from the overhanging edge 34 of the top 26, defining a space 35 through which the heated air from the openings 28 is educted.

The construction provided as above described, or its equivalent, is such that it can be made from wood or the like, so that all parts visible may correspond substantially with the furniture of the room in which it is 65 located and will overcome to a great extent the warping, twisting and buckling effect usually found with the use of wood adjacent to a heat diffusing element.

Having thus described my invention and 70 illustrated its use, what I claim as new and desire to secure by Letters Patent, is—

A radiator cover comprising a back, a front, opposed ends and a top, all connected into an organized, portable structure, said 75 front being provided adjacent the top with a row of openings spaced by intervening webs, a deflector spaced under the top with its front edge transecting the openings and inserted into and retained by the webs, and an overhang depending from the top and covering over and concealing the openings and said deflector front edge.

In witness whereof, I have signed this specification.

IRVING JACKSON.
